BUNION BRACE

Abraham L. Schenk, Los Angeles, Calif.

Application February 4, 1935, Serial No. 4,914

3 Claims. (Cl. 128—81)

This invention has to do in a general way with orthopedic appliances designed to correct deformities in the human foot. More specifically, my invention contemplates improvements in braces or supports designed to be worn upon a foot afflicted with an enlarged great toe joint or bunion for the purpose of holding a great toe so afflicted in its normal position with respect to the foot, whereby normal strength and action can be restored to the ligaments or tendons along the inside of the foot, which control the action of the great toe.

I am aware of the fact that various devices of this general character have been designed and used with varying degrees of success, and my invention contemplates improvements in this general type of appliance whereby it possesses certain advantages, both from the standpoint of the manufacturer and the user.

It is a primary object of this invention to produce a device of the class described which may be easily adjusted by the purchaser to suit either the right or the left foot. Another important feature of the appliance contemplated by this invention resides in the fact that it can be easily regulated so as to vary the tension applied to the toe by the brace.

It is a still further object of this invention to provide an appliance of the class described which can be worn with a minimum amount of discomfort arising out of the engagement of the foot with the appliance itself. With this object in mind, my invention contemplates providing any exposed edges in the appliance which engage the foot with cushioned means which prevent the formation of pressure ridges and skin irritation.

It is still another object of this invention to provide a device of the class described with improved means for attaching the same to the foot whereby it is securely held in its proper position.

The details in the construction of certain preferred forms of my invention, together with other objects attending its production, will be best understood from the following description of the accompanying drawing, which is chosen for illustrative purposes only, and in which

Fig. 1 is a perspective view illustrating the manner in which a preferred form of my invention is worn upon the foot;

Fig. 2 is a plan view illustrating further details in the construction of a preferred form of my invention;

Fig. 3 is a section taken along the line 3—3 of Fig. 2;

Fig. 4 is a fragmentary view illustrating a modi-

fied form of construction contemplated by this invention; and

Fig. 5 is a section taken along the line 5—5 of Fig. 4.

More particularly describing the invention as herein illustrated, reference numeral 11 indicates a brace or lever member which is composed of a single piece of relatively stiff wire 12, bent to form an elongated loop having an enlarged portion 13 at a substantial distance behind its front end. Stretched over and secured to this wire frame in any suitable manner is a membrane or a pliable piece of material, such as leather, which is indicated by reference numeral 14. In the region of the membrane occupying the enlargement 13, I provide an opening 16 formed by cutting out a portion of the membrane, thereby leaving a flap 17 secured to the membrane along the forward edge of the opening.

The flap 17 is then sewed or cemented to the forward portion of the membrane and since, as is clearly illustrated in Fig. 1, the appliance is worn by inserting the great toe T of the foot F through the opening 16, it will be observed that this flap 17 provides a cushion for the inside of the great toe and the folded edge formed by the flap at the front of the opening provides a smooth surface between the toes which eliminates any possible chafing or irritation that might be incurred in the event a "sharp" edge were located between the toes.

As a further means of adding to the comfort of the wearer, I propose to serrate the edge of the opening 16 as indicated at 18, so as to provide what is in effect a cushioned surface along the edge of the opening.

For the purpose of securing the brace member 11 to the foot, I provide what may be termed a "foot encircling strap" 20 which is attached to the membrane 14 at a substantial distance behind the opening 16 and is provided with a buckle 21 or any other suitable fastening means. In addition to the foot encircling strap 20, I provide what may be termed a "heel engaging strap" 22 which is also secured to the membrane 14 or the brace member 11, preferably adjacent the point of attachment for the foot encircling strap, the heel engaging strap passing through a loop 23 on the membrane and around the back of the heel, to a point where its free end may be attached to the side of the foot encircling strap opposite the brace. In this form of my invention the strap 22 is shown as being attached to the strap 20 through the medium of a buckle 24 mounted on the end of a connecting strap 25.

It was previously pointed out as a primary object of this invention to provide a device of the class described which could be worn either on the right or the left foot. This is accomplished by 5 making the wire frame 12, which forms the base for the lever or brace member 11, of symmetrical shape and attaching the foot encircling strap 20 to the membrane 14 in a manner such that it can be rotated through 180° as shown in broken lines 10 in Fig. 2. Also the connecting strap 25 is mounted on the strap 20 so that it can be readily removed and turned around. Various types of connections 15 may be employed in effecting these two last mentioned features. For the purpose of illustration, however, and in the preferred form of my invention as it is actually constructed, I attach the strap 20 to the membrane 14 through the medium of a friction buckle 29 which permits longitudinal adjustment of the strap 20, such buckle in turn 20 being attached to the membrane 14 by means of a rivet or other suitable connection indicated at 30, which permits free rotative movement of the buckle with respect to the membrane. The strap 25 is attached to the strap 20 by forming a loop 25 31 on the end of the strap 25. In this way the strap can be simply slipped off of the strap 20 and turned over when it is desired to use the device on the other foot.

With regard to the wire frame 12 it will be understood that such frame can be made in various 30 ways. As stated above, however, I prefer to form the same from a single piece of relatively stiff wire and, in order to eliminate any possible 35 projections which might cause discomfort to the wearer, I connect the ends of the wire together by undercutting them on adjacent sides through substantially half their diameter to form an overlapping joint as indicated at 33 and then brazing or welding the two overlapping sections together.

As shown in Fig. 1, the appliance is worn by 40 inserting the great toe through the opening 16 and then buckling the foot encircling and heel engaging straps. In this way the brace member 11, by virtue of the engagement of the inner surface 45 of the great toe with the membrane 14 is effective to press the great toe outwardly into or toward its normal position. It will be understood, of course, that while a device of this character need be worn only during periods of rest, it is necessary, to effect 50 any material correction, that such a device be worn consistently over a substantial period of time and in severe cases it may be that the tension applied to the great toe, with a view to effecting correction, must be gradually increased from the time of the first application until correction 55 has been completely effected. With this point in mind, it will be observed that the device contemplated by this invention lends itself particularly to such a condition, since it can be

easily adjusted so as to increase or decrease the tension which is applied to the great toe merely by bending the frame 12 in either direction.

In some instances it may be found desirable 5 to provide means for preventing vertical movement of the toe while the brace is being worn and, in the modified form of my invention shown in Figs. 4 and 5, I show the forward end of the brace member 11' as being provided with a loop 10 35 adapted to fit over the great toe when the appliance is being worn. In this form of my invention I also show another modification in the cushioning means which surround the opening 16'. Such cushioning means comprises an edge binding of some suitably soft fabric indicated by 15 reference numeral 36.

It will be understood that while I have herein 20 described and illustrated certain preferred forms of my invention the invention is not limited to the precise construction described above but includes within its scope whatever changes fairly come within the spirit of the appended claims.

I claim as my invention:

1. A foot correcting appliance embodying: an 25 elongated, substantially symmetrical wire frame; a pliable membrane fitted over and secured to said frame, said membrane having an opening therein adapted to receive the great toe; a foot encircling strap pivotally attached to said membrane behind 30 said opening; and a heel engaging strap having one end secured to said membrane and having its other end adapted to be secured to said foot encircling strap on the side opposite said membrane.

2. A foot correcting appliance embodying: an 35 elongated, substantially open frame; a pliable membrane stretched over and secured to said frame, said membrane having an opening therein adapted to receive the great toe; a foot encircling strap secured to said membrane behind said opening; and a heel engaging strap having one 40 end secured to said membrane and having its other end secured to said foot encircling strap on the side opposite said membrane, said opening being provided with a cushioned edge.

3. A foot correcting appliance embodying: an 45 elongated wire frame; a pliable membrane fitted over and secured to said frame, said membrane having an opening therein adapted to receive the great toe; a foot encircling strap attached to said membrane behind said opening; a heel 50 engaging strap having one end secured to said membrane and having its other end adapted to be secured to said foot encircling strap on the side opposite said membrane; and means secured to said appliance in front of said opening for supporting the great toe against vertical movement.

ABRAHAM L. SCHENK.
